His Attorney.

UNITED STATES PATENT OFFICE

DAVID C. PRINCE, OF SCHENECTADY, NEW YORK, ASSIGNOR TO GENERAL ELECTRIC COMPANY, A CORPORATION OF NEW YORK

ELECTRICAL SYSTEM

Application filed August 23, 1926. Serial No. 131,017.

My invention relates to electrical systems wherein power is transmitted through a space discharge device connected between circuits operated under different electrical conditions, and has for its principal object the provision of an improved apparatus and method whereby the relation between the electrical conditions of such circuits may be readily controlled and maintained.

Various arrangements have been proposed for maintaining a desired relation between the frequencies or the other electrical conditions of two circuits interconnected through a space discharge device. In many of these arrangements, this relation is maintained by means comprising a grid arranged to control the transmission of current between the cathode and anode of the space discharge device. My improved apparatus is similar in some respects to the aforesaid arrangements but differs therefrom in that the circuits are interconnected through a space discharge device which need not be provided with a grid and in that means comprising an electrical valve are provided for ensuring that the proper relation between the electrical conditions of the circuits is maintained.

My invention will be better understood from the following description when considered in connection with the accompanying drawing and its scope will be pointed out in the appended claims.

The drawing illustrates an apparatus wherein my invention is utilized for the purpose of transmitting power between alternating and direct current circuits.

This apparatus comprises direct current terminals 1 and alternating current terminals 2 which are interconnected through means illustrated as a smoothing reactor 3, a transformer 4, electrical valves 5 and 6 and a space discharge device 7. The valves 5 and 6 are preferably of the magnetostrictive type disclosed by Letters Patent of A. W. Hull, No. 1,523,778. As indicated by the drawing, the valve 5 comprises a cathode 11 surrounded by a cylindrical anode 12 and the valve 6 comprises a cathode 13 surrounded by a cylindrical anode 14.

It will be observed that the transformer 4 is provided with a winding 8 which has its end terminals connected to the anodes 12 and 14, with a winding 9 which is connected to the alternating current terminals 2 and with a winding 10 which has its end terminals connected through current transformers 25 and 26 to the cathodes 11 and 13 of valves 5 and 6. The space discharge device 7 comprises a vaporizable cathode 15, a starting electrode 16, an exciting electrode 17, and main anodes 18 and 19 which are connected to the end terminals of the winding 10 through current transformers 25 and 26 and the cathodes 11 and 13. A source 20 and switch 21 may be provided for initiating operation of the apparatus.

The frequency of the current supplied through the alternating current terminals 2 may be controlled by means of a capacitor 22 connected to the winding 8 or by any other suitable means such as the capacitance of the alternating current circuit.

In the operation of systems of the type described, it is necessary for efficient and satisfactory operation that current should be allowed to start through one anode of the space discharge device before it is completely interrupted in the anode from which the current is being transferred. It is also desirable that the transfer of current from one anode to another should occur before the potentials of these anodes become equal. These results are produced by means comprising the capacitors 23 and 24 which are connected through the transformers 25 and 26 to the terminals of the winding 10 in series relation with cathodes of valves 5 and 6 and the anodes of device 7.

As set forth in the aforementioned Letters Patent, the conductivity of the valves 5 and 6 is dependent on the magnitude of the heating current transmitted through the cathodes 11 and 13. Thus assuming that a given voltage is applied between the cathode 13 and the anode 14 and that the heating current of the cathode 13 is gradually increased from zero, current is transmitted through the valve 6 until the magnetic field produced by the cathode heating current is sufficiently strong

to deflect the electrons from the anode. When this occurs, the circuit through the valve 6 is interrupted. Opening of the valve is produced by decrease in the strength of the cathode heating current and magnetic field.

5 The heating current of cathodes 11 and 13 is started either by the source 20 or by current supplied through the alternating current terminals 2 and is thereafter supplied from the winding 10 which is inductively related 10 to the winding 8 and is connected at a point intermediate its end terminals through a ground connection to the cathode 15. As previously indicated, the frequency at which the 15 current is transferred between the two halves of the winding 8 is dependent on the adjustment of the capacitor 22.

Suppose a source of positive direct current potential to be attached at terminal 1 and 20 the phase of the alternating receiving circuit attached to terminals 2 to be such that the right hand end terminals of winding 8 is positively charged; current is then transmitted from the left end of winding 8 through 25 anode 12 to cathode 11 where it divides, one part passing to ground through anode 18 of device 7 and the other part passing to ground through winding 10. Due to the division of 30 this current and to the fact that the current itself is relatively small, no magnetic field is set up sufficient to render device 5 non-conducting. At the same time the right end terminal of winding 10 is positively charged by 35 induction from windings 8 and 9, and current from it passes through current transformer 26, cathode 13, anode 19 to ground. This current traverses cathode 13, thus establishing the magnetic field which renders valve 6 non-conducting.

40 As the phase of the voltage in windings 8, 9 and 10 progresses, the current through filament 13 dies down until it falls below the value necessary to render device 6 non-conducting. Current then begins to flow from 45 the right end terminal of winding 8 through anode 14 to cathode 13 in which it divides, flowing to ground by winding 10 and device 7. Since the total current is rendered nearly constant by inductance 3, current through device 5 falls as it rises through device 6. Current now begins to flow from the left hand 50 terminal of winding 10 through filament 11, thus rendering device 5 non-conducting. Suitable advance in phase of the cathode current is obtained by voltages built up across 55 capacitors 23 and 24 inductively connected to the devices 5 and 6 through transformers 25 and 26. The further operation of the apparatus will be readily understood in view 60 of the foregoing illustration.

The embodiment of the invention illustrated and described herein has been selected for the purpose of clearly setting forth the principles involved. It will be apparent, 65 however, that the invention is susceptible of

being modified to meet the different conditions encountered in its use and I therefore aim to cover by the appended claims all modifications within the true spirit and scope of my invention.

70 What I claim as new and desire to secure by Letters Patent of the United States, is:—

1. The combination of alternating and direct current terminals, and means comprising a space discharge device provided with a cathode and anode, a cathode-anode circuit including said space discharge device and comprising said direct current terminals and a magneto-strictive element connected in series with said anode, means associated with 75 said circuit arranged to produce a voltage which varies in accordance with the anode potential of said space discharge device, means to transfer power between said last named means and said alternating current terminals, and means responsive to the cathode-anode current in said circuit for controlling the magneto-strictive effect of said element.

2. The combination of alternating and direct current terminals, and means comprising a space discharge device provided with a cathode and anode, a cathode-anode circuit including said space discharge device and comprising said direct current terminals and an 80 electrical valve connected in series with said anode, means associated with said circuit arranged to produce a voltage which varies in accordance with the anode potential of said space discharge device, means to transfer power between said last named means and said alternating current terminals, and means arranged to control the operation of said valve in accordance with the cathode-anode 85 current in said circuit.

90 3. The combination of alternating and direct current terminals, and means comprising a space discharge device provided with a cathode and anode, a cathode-anode circuit including said space discharge device and comprising said direct current terminals and a valve having a cathode and an anode connected in series with said anode of said discharge device, a transformer connected in 95 said circuit arranged to produce a voltage which varies in accordance with the cathode-anode current in said circuit, means to transfer power between said transformer and said alternating current terminals, and means interconnected with said transformer for supplying cathode heating current to said valve.

100 4. The combination of alternating and direct current terminals, and means comprising a space discharge device provided with a cathode and anode, a cathode-anode circuit including said space discharge device and comprising said direct current terminals and a valve having a cathode and an anode connected in series with said anode of 105 said space discharge device, means associ- 110

ated with said circuit arranged to produce a voltage which varies in accordance with the anode potential of said space discharge device, means to transfer power between said last named means and said alternating current terminals, means interconnected with said voltage producing means for supplying cathode heating current to said valve, and phase control means connected in circuit with 10 said voltage producing means and said cathode of said valve.

5. The combination of alternating and direct current terminals, and means comprising a space discharge device provided with a 15 cathode and anode, a cathode-anode circuit including said space discharge device and comprising said direct current terminals and a valve having a cathode and an anode connected in series with said anode of said space 20 discharge device, means associated with said circuit arranged to produce a voltage which varies in accordance with the anode potential of said space discharge device, means to transfer power between said last named 25 means and said alternating current terminals, means connected with said voltage producing means for supplying cathode heating current to said valve, and a capacitor interconnected with said cathode heating current 30 supply means.

6. The combination of a pair of alternating and a pair of direct current terminals, and means comprising a transformer provided with one winding connected between 35 said pair of of alternating current terminals and with another winding connected at a point intermediate its end terminals to one of said direct current terminals, a plurality of magneto-strictive elements, a space discharge device provided with anodes each 40 connected to a different one of said end terminals through a different one of said magneto-strictive elements, and means arranged to control the cathode heating currents of 45 said magneto-strictive elements in accordance with the anode potentials of said space discharge device.

7. The combination of different pairs of terminals, and means comprising a transformer provided with one winding connected between one of said pairs and with another winding connected at a point intermediate its end terminals to one terminal of another of said pairs, a plurality of electrical valves, 55 a space discharge device provided with anodes each connected to a different one of said end terminals through a different one of said valves, and means arranged to control the cathode heating currents of said valves in accordance with the anode potentials of said space discharge device.

8. The combination of different pairs of terminals, and means comprising a transformer provided with one winding connected 60

between one of said pairs and with another winding connected at a point intermediate its end terminals to one terminal of another of said pairs, a plurality of electrical valves, a space discharge device provided with anodes each connected to a different one of said end terminals through a different one of said valves, means arranged to control the cathode heating currents of said valves in accordance with the anode potentials of said space discharge device, and means for controlling the phase relation between the anode heating currents of said valves and the anode potentials of said space discharge device.

In witness whereof, I have hereunto set 80 my hand this 20th day of August, 1926.

DAVID C. PRINCE.
